UNITED STATES PATENT OFFICE.

JOSEPH B. SMYTHE, OF COATICOOK, QUEBEC, CANADA.

RATCHET MECHANISM.

1,090,578.

Specification of Letters Patent. Patented Mar. 17, 1914.

Application filed June 10, 1911. Serial No. 632,510.

To all whom it may concern:

Be it known that I, JOSEPH B. SMYTHE, a subject of the Kingdom of Great Britain, and a resident of Coaticook, Province of Quebec, Canada, have invented certain new and useful Improvements in Ratchet Mechanism, of which the following is a specification.

This invention relates to ratchet mechanism, pawls and ratchets, particularly adapted for use with lifting jacks, and particularly to that class of jacks which are known as ratchet screw jacks, and which are manipulated by an operating handle carrying a double ended pawl, either end of which is adapted to engage with the ratchet wheel on an operating shaft.

The object of the present invention is to provide an increased working surface between the pawl and the ratchet wheel, thereby obviating the danger of splitting the ratchets when in operation, and make it possible to operate the ratchet mechanism with a decreased movement of the operating lever.

The invention consists in providing the operating lever with a socket having a transverse slot in which is positioned the ratchet wheel secured to the shaft of the operating gear, and interposing between said ratchet wheel and one wall of the socket a reciprocating pawl having a set of teeth at each end thereof, either of which is adapted to be brought into position to coact with the ratchet teeth to effect the raising or lowering of the jack as desired.

The invention further consists in certain novel features of construction and arrangement of parts which will be thoroughly understood by reference to the description of the drawings and to the claims hereinafter given.

Of the drawings: Figure 1 represents a vertical section of a jack embodying the features of the present invention. Fig. 2 represents a section of the gear operating mechanism, the cutting plane being on line 2—2 on Figs. 1 and 3. Fig. 3 represents a vertical section of the same, the cutting plane being on line 3—3 on Fig. 2, and Fig. 4 represents a transverse vertical section of the same, the cutting plane being on line 4—4 on Fig. 2.

Similar characters designate like parts throughout the several figures of the drawings.

In the drawings, 10 represents a suitable base supporting the stationary standard 11 over the outer periphery of which is fitted a movable sleeve 12, to the upper end of which is threaded a head 13. In the upper end of the head 13 is mounted a plate 14, between the under face of which and the upper face of a beveled gear 15 is interposed a plurality of anti-friction members 16. The gear 15 is splined to the reduced upper end of a screw 17, the threaded end of which is threaded to a nut 18 mounted in the upper end of the standard 11. The gear 15 meshes with the gear 19 secured to or formed upon a revolute shaft 20 mounted in a bearing 22 on the side of the movable member 12. To the reduced end of the revolute shaft 20 is splined or otherwise secured the ratchet wheel 23, positioned within a slot 24 of a socket member 25. This socket member 25 when in use has inserted therein a handle 26 as indicated in dotted lines in Fig. 2 of the drawings, which handle may be moved by the operator to cause an oscillation of the socket member 25 about the shaft 20 upon which it is free to move in either direction, said socket member being retained in position upon said shaft 20 by means of a cotter pin or similar member 27. The ratchet wheel 23 is provided throughout its periphery with a plurality of V-shaped teeth 28. Interposed between this ratchet wheel 23 and one end face 29 of the slot 24 is a reciprocating wedge member 30. One face of the member 30 is flat and bears against the flat face 29 of the slot 24, while the opposite face is provided at either end with a plurality of V-shaped teeth 31. Between these sets of teeth 31 is a connecting portion 32 having a short flat face 33 parallel to the back face of the member 30, and normally in contact with the ends of the teeth 28. Each set of teeth 31 is arranged in the arc of a circle, the radius of which is the same as that of the ratchet wheel 23, so that when either set of teeth 31 are in engagement with the ratchet teeth 28, all said teeth accurately fit one another and the working surface is thereby greatly increased over a ratchet mechanism such as has usually been used, in which a single pawl coacts with the ratchet teeth. This construction insures a better grip for operating the jack and owing to the increased gripping surface there is no splitting strain on the mechanism, as when the pawl is in action it wedges itself be-

tween the ratchet wheel and the wall 29 of the socket.

It is obvious from an inspection of Fig. 3 of the drawings, that when the socket is moved about the shaft 20 in the direction of the arrow thereon, the ratchet teeth 31 will so coact with the ratchet teeth 28 as to cause the member 30 to become wedged between the ratchet wheel 23 and the wall 29 and insure a rotary movement of the shaft 20, while permitting, in the return movement of the socket 25, the teeth 31 to pass over the teeth 28, preparatory to securing another grip thereon. This slight movement of the member 30 to permit its teeth to pass the teeth of the ratchet wheel during the return movement is effected by means of the notch 34 cut in the side face of the pawl member 30, and coacting with the V-shaped end of a locking member 35 positioned in a recess in the socket member 25 and pressed inwardly into contact with one wall of the notch 34 by means of the spring 36. During the return movement of the socket the locking member 35 will be retracted slightly against the tension of the spring 36 to permit the teeth of the two members to pass one another. The locking member 35 is prevented from turning in its recess and from being accidentally displaced therefrom by means of the screw 37. When it is desired to lower the jack, the member 30 is pressed through the slot in the socket 25 until the notch 38 engages the locking member 35, thereby bringing the other set of teeth 31 into action. It is obvious that during the raising and lowering of the handle 26 the reciprocating pawl member 30 will automatically engage and disengage the ratchet either when lowering or raising the jack. In order to reduce the frictional contact between the member 30 and the wall 29 as it reciprocates in the slot in the socket 25, portions of the rear face of said member are cut away as indicated at 38, this also serving to reduce the weight of the pawl member.

In the ordinary ratchet mechanism where a single point on the pawl is used for lifting and another single point on the pawl is used for lowering, there is always a great danger of splitting the ratchets owing to the great multiplication of power, while in the present construction, with the increased area of the gripping surface, this danger is wholly overcome. While the action of the device is very powerful, owing to the pawl when in operation wedging itself between the ratchet and the wall of the slot, the pawl releases very easily to permit the teeth to pass on the return stroke. Another advantage is that the back lash in the present construction is greatly reduced over that of the ordinary pawl and ratchet in general use. Moreover, owing to the increased number of teeth in the pawl in engagement with the ratchet, the

lever may be worked in a much smaller space than in the ratchet mechanisms generally used.

It is believed that the operation and many advantages of the invention will be thoroughly understood from the foregoing.

Having thus described my invention, I claim:

1. In a device of the class described, the combination of a spindle, an oscillating lever on said spindle provided with a socket having a transverse slot therein one wall of which is straight and unobstructed; a wheel within said slot secured to said spindle and provided with a serrated peripheral surface; a slidable wedge member in said slot restricted in its movement to a path tangential to said wheel by a flat face contacting with said straight wall and provided on its opposite face with a curved serrated surface coacting with the periphery of said wheel; and means providing a limited sliding movement of said wedge member during each oscillation of said lever.

2. In a device of the class described, the combination of a spindle, an oscillating lever on said spindle provided with a socket having a transverse slot therein one wall of which is straight and unobstructed; a wheel within said slot secured to said spindle and provided with a serrated peripheral surface; a slidable double-ended wedge member in said slot having a flat face contacting with said straight wall and thereby restricted in its movement to a path tangential to said wheel and provided on its opposite face with a curved serrated surface at each end either of which is adapted to coact with the periphery of said wheel; and means providing a limited sliding movement of said wedge member during each oscillation of said lever.

3. In a device of the class described, the combination of a spindle; an oscillating lever on said spindle provided with a socket having a transverse slot therein having parallel unobstructed end walls; a wheel within said slot secured to said spindle and provided with a serrated peripheral surface; a slidable double-ended wedge member in said slot having a flat base contacting with the outer end wall of said slot and thereby restricted in its movement to a path tangential to said wheel and provided on its opposite face with a curved serrated surface at each end either of which is adapted to coact with the periphery of said wheel, said curved serrated surfaces being connected by a flat face contacting with the periphery of said wheel; and means providing a limited sliding movement of said wedge member during each oscillation of said lever.

4. In a device of the class described, the combination of a spindle; an oscillating lever on said spindle provided with a socket

having a transverse slot therein; a wheel within said slot secured to said spindle and provided with a serrated peripheral surface; a slideable double-ended wedge member in said slot restricted in its movement to a path tangential to said wheel and provided with a curved serrated surface at each end either of which is adapted to coact with the periphery of said wheel, said member being provided with two notches intermediate its ends; and means coöperating with either of said notches to retain said member in position for one selected curved serrated surface to coact with said wheel while permitting a limited reciprocation to said member during each oscillation of said lever.

5. In a device of the class described, the combination of a spindle; an oscillating lever on said spindle provided with a socket with a transverse slot therein; a ratchet wheel within said slot secured to said spindle and provided with V-teeth; a slideable member in said slot provided with two sets of V-teeth adapted to coact independently with said ratchet teeth and having two notches therein; and a spring-pressed member having an end adapted to engage either notch which end is of less width than that of the coacting notch.

6. In a device of the class described, the combination of a spindle; an oscillating lever on said spindle provided with a socket with a transverse slot therein having parallel unobstructed end walls; a wheel within said slot secured to said spindle provided with a serrated peripheral surface; a slideable double ended wedge member in said slot normally having a limited movement in a straight path with its base contacting with the outer end wall of said slot and provided at each end of its opposite face with a curved serrated surface, said curved surfaces being

adapted to coact independently with the serrated periphery of said wheel; and locking means permitting said limited movement 45 of said slideable member and adapted to be operated to permit either curved serrated surface to be brought into action.

7. In a device of the class described, the combination of a spindle; an oscillating 50 lever on said spindle provided with a socket with a transverse slot therein; a wheel within said slot secured to said spindle provided with a serrated peripheral surface; a slideable member in said slot provided with two 55 curved serrated surfaces adapted to coact independently with said wheel periphery and having two notches therein; and a spring pressed member having an end adapted to engage either notch which end is of 60 less width than that of the coacting notch.

8. In a device of the class described, the combination of a spindle; an oscillating lever on said spindle provided with a socket with a transverse slot therein; a wheel within 65 said slot secured to said spindle provided with a serrated peripheral surface; a slideable member in said slot provided with two curved serrated surfaces adapted to coact independently with said wheel periphery 70 and having two notches therein; a spring pressed member having a tapered end adapted to engage either notch; and a stop preventing the tapered end of said spring pressed member extending to the bottom of 75 said notches thereby permitting a limited movement to said slideable member.

Signed by me at 4 Post Office Sq., Boston, Mass., this 19th day of May, 1911.

JOSEPH B. SMYTHE.
